DESIGN FOR A GLIDER SWING

Matthew L. Drewniak, Buffalo, N. Y.

Application April 15, 1946, Serial No. 128,611

Term of patent 7 years

(Cl. D15—11)

To all whom it may concern:

Be it known that I, Matthew L. Drewniak, a citizen of the United States, residing at Buffalo, in the county of Erie and State of New York, have invented a new, original, and ornamental Design for a Glider Swing, of which the following is a specification, reference being had to the accompanying drawing, forming a part thereof.

Figure 1 is a side view of the glider swing embodying my new design. Figure 2 is a top plan view thereof. Figure 3 is an end view of the same.

I claim:

The ornamental design for a glider swing, substantially as shown.

MATTHEW L. DREWNIAK.
